UNITED STATES PATENT OFFICE.

JOCHIM H. HAMAN AND CHRISTIAN HAMAN, OF OMAHA, NEBRASKA.

EARTH SCAPER AND ELEVATOR.

SPECIFICATION forming part of Letters Patent No. 320,553, dated June 23, 1885.

Application filed December 10, 1883. (No model.)

To all whom it may concern:

Be it known that we, JOCHIM H. HAMAN and CHRISTIAN HAMAN, of Omaha, in the county of Douglas and State of Nebraska, citizens of the United States, have invented certain new and useful Improvements in Carrier-Excavators; and we hereby declare that the following is a full, clear, and exact description of the same, reference being had to the accompanying drawings, in which—

Figure 1 is a plan view of a machine embodying our improvements. Fig. 2 is a side elevation. Fig. 3 is a side elevation taken from the side opposite to that shown in Fig. 15. Fig. 4 is a rear elevation. Fig. 5 is a front elevation. Fig. 6 is a detail view showing the rear axle in section, the inner face of one of the driving-wheels, one of the spring-actuated pawls, and one of the ratchets. Fig. 20 7 is a detail view.

Our invention has relation to carrier-excavators designed for excavating and ditching; and it consists in the construction and novel arrangement of parts, as will be hereinafter 25 fully described, and particularly pointed out in the claims.

Referring by letter to the accompanying drawings, A designates the frame of the elevator. This frame is provided near its rear end 30 with drive-wheels B B, having traction-pins in their peripheries. The front axle is provided with a tongue by which the machine is to be drawn, and a rack, C, extends upwardly from the front axle through the front cross- 35 beam of the frame and engages a pinion supported in bearings rising from the front of the frame; and a crank, double pawls, and double ratchets are employed to hold the front end of the frame to its adjustments, which are vertical, and are intended to regulate the depth 40 of the cut of the scraper. An adjustable rotary cutter, E, is suspended in the lower ends of rack-arms F, working vertically in bearings F⁴, secured to the inner faces of the side 45 beams of the main frame, near the forward end of the same, and engaging pinions F' on a shaft F², provided with a crank, F³, at one end. These rack-arms F are perforated and held to their adjustments by set-screws F⁵. An adjustable scraper, G, provided with parallel 50 shares G', is connected to the lower ends of

inverted-U-form frames H, the parallel arms of which are perforated and secured in bearings H' by thumb-screws H². Middle rack-bars, H³, connect the shares of the scraper with the curves of the U-form frames, and inclined braces H⁴ connect the arms of the U-frames and the rack-bars intermediate of the arms of the inverted-U frames at the sides of the vertically-adjustable scraper. Pivoted arms H⁵ 60 connect the inclined braces H⁴ with the stay-chains H⁶, which are in turn connected to a transverse shaft, H⁷, secured in bearings at the sides of the main frame near its forward end. This transverse shaft, H⁷, is provided with 65 ratchets and detents H⁸ near each end inside of the framing, which prevent backward rotation of said shaft H⁷ when the ratchets and detents are in engagement, and a crank common to the several transverse shafts is employed to turn this shaft H⁷ to regulate the tension on the chains H⁶ H⁶. The transverse shafts employed in this construction are provided with crank handles to effect the necessary adjustment of the parts. The driving-wheels B B are mounted on the rear shaft, B', and are provided with half-clutches B², 70 with ratchet-teeth on their peripheries, which are engaged by spring-pressed detents B³, to permit backward movement of the driving-wheels B B when the half-clutches B² B² are in engagement with the sliding half-clutches B⁴ on the axle B'. The sliding half-clutches B⁴ are provided with peripheral grooves, which are engaged by forks B⁶ at the 75 upper ends of spring-actuated levers B⁷, fulcrumed to the lower ends of hangers B⁸, depending from the lower halves of the boxes B⁹, which support the shaft B'. Beneath the boxes B⁹, and fulcrumed on the hangers B⁸, are angle-levers B¹¹, the rear arms of which are connected by wire rods B¹² to the arms of the spring-actuated levers B⁷. The front arms of the angle-levers B¹¹ are connected by wires C to angle-levers C', fulcrumed to the frame of 90 the machine in front of the inverted-U frames. The angle-levers C' are connected to each other by a transverse rod, C², and one of the angle-levers, C', is connected to a lever, C³, by a rod, C⁴, said lever C³ having a 95 detent-lever, C⁵, which engages an arc rack, C⁶, toothed in the lower edge of its arc, and

holds the clutch mechanism out of engagement when desired. The axle B' is provided with two spur gear-wheels, D D', inside the side rails of the main frame. The gear-wheels D D' engage pinions D² D³, in front of them, on a transverse shaft D⁴, having bearings in hangers D⁵ D⁶, depending from the inner faces of the side rails of the frame. Just outside of the pinions D² D³ the transverse shaft D⁴ is provided with sprocket-wheels D¹¹ D¹¹, which are connected by sprocket-chains D⁶ D⁶ with the outer sprocket-wheels, D⁷ D⁷, on the lower shaft, D⁸, of the endless elevator E. The lower shaft, D⁸, of the elevator E is also provided with sprocket-wheels D⁹ D⁹ and sprocket-chains connected by the buckets D¹⁰ to form the elevator E. The frame F¹⁰ of the elevator E inclines upwardly and rearwardly for a portion of its length, its arms F¹¹ being slotted and extended vertically. The frame G of the elevator E is provided with bearings for the upper shaft, G', which latter is also provided with sprocket-wheels G², and the ends of the shaft G' project through the slots G³ in the frame F¹⁰. This arrangement permits an adjustment of the elevator E, which has its bearings in the forward ends of arc rack X, working in guides X', secured to the inner faces of the side rails of the frame directly opposite the lower end of the elevator E. The teeth of the arc rack X engage pinions X² X², and the pinions X² X² engage pinions X³ X³ on the transverse shaft X⁵, having bearings X⁴ immediately in front of the elevator E. The transverse shaft X⁵ is provided with ratchet-wheels X⁶ X⁶ near its pinions X² X², and these ratchet-wheels X⁶ X⁶ are engaged by spring-pressed pawls X⁷ X⁷, which prevents backward movement of the shaft X⁵.
 40 In the rear of the elevator E, in bearings rising above the side timbers of the frame of the machine, is journaled a transverse shaft, I, which is provided with a pinion, I', which engages a pinion, I², beneath it on a short shaft, I², extending inwardly from a shoulder on the side beam of the frame, and the pinion I² engages the gear-wheel on the driving shaft beneath it. On the end of the transverse shaft I, just inside of its bearing, is a miter-gear, I⁴, which engages a miter-gear, J, on the front end of the longitudinally-disposed lower shaft, J', of the side carrier, J², which is located at the rear of the frame and transversely of the frame. The upper and lower shafts of the side carrier are also provided with sprocket-wheels, and its buckets connect sprocket-chains which run over the sprocket-wheels. The side carrier is made in two sections, K and K', hinged together, and the upper section, K', is provided with hangers which sup-

port a roller, K², which prevents sagging of the under portion of the endless carrier. The upper section, K', of the endless carrier is provided with a hinged bail, K³, and with angular stops K⁴, which prevent the bail from interfering with the buckets of said carrier. The bail K³ is provided with an eye at its middle, and to this eye is connected a rope, L, which extends over a pulley, L', in a strap-guide, L², at the upper end of a standard at the rear right corner of the frame, and runs down and connects with a winch near the lower end of the standard. The winch is provided with a ratchet and pawl to prevent accidental backward movement of the same. The lower section of the side carrier is suitably braced, while the upper section may be raised and lowered or turned on its hinges to change its inclination, as may be required in operating the machine, in the ditch to properly discharge the dirt at the side of the ditch as it becomes deeper.

Having thus fully described our invention, what we claim as new, and desire to secure by Letters Patent of the United States, is—

1. The combination, with the main frame provided with the bearings F⁴ and set-screws F⁵, of the rotary cutter E, the rack-arms F, and the shaft F², provided with the crank F³, substantially as specified.

2. The combination, with the frame A, provided with the bearings H', of the scraper G, the inverted-U frames H, with perforated parallel arms, thumb-screws H², middle rack-bars, H³, inclined braces H⁴, pivoted arms H⁵, stay-chains H⁶, and the transverse shaft H', with ratchets and detents H⁸, substantially as specified.

3. The combination, with the frame A, provided with the endless elevator E, and mechanism, substantially as described, for operating said elevator E, of the hinged side carrier provided with the supporting-roller K², the bail K³, rope L, pulley and strap guide on the corner standard, and the winch, pawl, and ratchet for operating the rope, substantially as specified.

4. The combination of the main frame, the endless elevator E, the elevator-frame F¹⁰, having vertical slotted arms, curved racks hinged to the lower end of the elevator-frame G, guides in the main frame for the curved racks, and gears moving the curved racks and raising or lowering the elevator, substantially as described.
